US00D870262S

(12) **United States Design Patent** (10) Patent No.: **US D870,262 S**
 (45) Date of Patent: ** *Dec. 17, 2019

(54) **ICE MELTING TABLET FOR MELTING ICE AND SNOW**

(71) Applicant: **Van M. Kassouni**, Grand Rapids, MI (US)

(72) Inventor: **Van M. Kassouni**, Grand Rapids, MI (US)

(*) Notice: This patent is subject to a terminal disclaimer.

(**) Term: **15 Years**

(21) Appl. No.: **29/623,107**

(22) Filed: **Oct. 23, 2017**
